JOSEPH A. ANGLADA, OF PHILADELPHIA, PENNSYLVANIA, ASSIGNOR TO BAKER WHEEL & RIM COMPANY, OF CHICAGO, ILLINOIS, A CORPORATION OF ILLINOIS.

METAL WHEEL.

1,336,334.

Specification of Letters Patent.

Patented Apr. 6, 1920.

Application filed May 17, 1918. Serial No. 235,116.

To all whom it may concern:

Be it known that I, JOSEPH A. ANGLADA, a citizen of the United States, and a resident of Philadelphia, county of Philadelphia, and 5 State of Pennsylvania, have invented certain new and useful Improvements in Metal Wheels, of which the following is a specification.

My invention relates to improvements in 10 and upon, and for the manufacture of, wheels, more especially motor vehicle wheels;—and its object is to so modify the construction, design and distribution of parts that they may be rapidly and cheaply 15 made from sheet material, and greatly improved in strength, resilience, efficiency, stability and durability, and shall be safer, of less weight, of less cost, silent, and easier to keep clean. A further object is to provide 20 a wheel construction which shall lend itself to beauty of design, and any desired finish. Another object of my invention is to provide a metallic vehicle wheel of the suspension type but which shall be formed 25 from sheet metal, as distinguished from the so-called wire wheels in present use. A special object of the invention is to provide a method of producing metal wheels from sheet and strip metal in a simple, inexpensive manner and at low cost; and particularly 30 to provide a method whereby such wheels may be made substantially without waste of material.

The invention resides, primarily, in a resilient wheel of the suspension type, mainly 35 formed or stamped from a sheet or plate of material (such as sheet steel), and which, by various changes in configuration may be presented in many forms and designs, and 40 adapted to many different uses. The invention also consists in details of design, construction, and combination of parts, as hereinafter described and particularly pointed 45 out in the appended claims.

My invention will be more readily understood 50 by reference to the accompanying drawings wherein I have shown what I consider to be the best embodiments of my novel invention including method of producing the wheel.

In the said drawings: Figure 1 represents a portion of sheet metal from which I produce the wheel, and also indicates the first 55 step in the method of stamping or cutting

2 is a view illustrating the second step in forming the wheel, the same being a part or blank stamped or sheared from the sheet and then shaped to cylindrical form;—Fig. 3 illustrates the next step in the formation 60 of the wheel, to-wit:—the forming of the part shown in Fig. 2 to a shape suitable for attachment to the hub flange of a wheel hub;—Fig. 4 is a fragmentary view similar 65 to Fig. 2, but illustrating, by means of dotted lines, how that portion of the wheel which forms the outside spoke portion is shaped;—Fig. 5 is a transverse sectional view illustrating the shaped spoke or body portions of the wheel in initial assembling 70 relation without a wheel hub but with the peripheral member, in this case the metal felly;—Fig. 6 is similar to Fig. 5 but illustrates the assembled relation of the parts;—Fig. 7 is a face view of a wheel of the form 75 shown in Figs. 5 and 6, together with a demountable rim, pneumatic tire, and the usual rim-clamping lugs;—Fig. 8 is a vertical section substantially on the lines 8—8 of Fig. 7;—Fig. 9 is like Fig. 8, the difference being 80 that Fig. 8 illustrates a rear or driving wheel having a brake drum, whereas Fig. 9 shows the wheel as it appears when used as a steering wheel;—Figs. 10, 11, 12, 13, 14 and 15, are sectional views illustrating modifications of my invention and adaptations 85 thereof to pneumatic-tire carrying, demountable rims; to pneumatic-tire carrying, non-demountable rims, and to solid rubber tires;—Fig. 16 is a vertical, sectional view 90 showing a modification of my invention as embodied in a broad truck wheel;—Fig. 17 is a detail, sectional view illustrating my invention as applied to a pneumatic tire rim which has a detachable side flange;—Fig. 95 18 is a view illustrating a modification in which a demountable, quick-detachable rim is mounted upon the wheel felly;—Figs. 19 and 20 are fragmentary plan views showing methods of securing the spoke ends in the 100 wheel felly;—Figs. 21 and 22 are respectively fragmentary views, partially in elevation and partially in section, of the spoke securing method shown in Fig. 20;—Figs. 23 and 24 are fragmentary sectional views 105 of the felly portion of the wheel showing modified methods of securing the spoke ends in place; and Fig. 25 is a fragmentary sectional view illustrating a modified method of joining the body of the wheel to the hub. 110

Because of its low cost and its excellent qualities, I prefer sheet metal (either hot rolled or cold rolled) as the material from which my wheels shall be made. The thickness of the sheet is proportioned to the service which the wheel is to perform. In making passenger car wheels (as distinguished from truck wheels) I prefer sheet steel of about one-eighth inch in thickness, 5 as that material yields a wheel of approximately the same weight as a corresponding wooden artillery wheel and of much greater strength and stability. The diameter, the hub length (within reasonable limits) the 10 width of the peripheral flanges and the width of the spokes may be varied to suit load and service requirements and the designer's conception of proportions and beauty. Most of the exemplary wheels 15 herein shown are motor vehicle wheels of familiar diameters and hub lengths.

I am aware that it has been proposed heretofore to manufacture metallic vehicle wheels from sheet metal, but in the methods 20 heretofore prevailing, great wastage of material has resulted due very largely to the methods of manufacture, which usually consisted in stamping or pressing the complete circular wheel body out of a square or 25 rectangular sheet of metal. This has been the usual method whether the wheel were of the so-called disk type or of the spoke type. The wastage referred to resulted not only from the manufacture of a circular 30 wheel from a square or rectangular sheet of metal, but also in those types having spokes, from the removal of very considerable portions of metal between adjacent 35 spokes. It is one of the objects of my invention practically to eliminate this expensive 40 wastage of material.

In practising my invention, I prefer, instead of using a square sheet of metal, to start with a long sheet or wide strip of 45 rectangular shape, the width of which is equal substantially to the outer circumference of the hub portion of the wheel to be formed, and the length of which is such as to enable the progressive or simultaneous 50 production of a plurality of blanks or members of a character suitable for the major or spoke portion of the wheel. In the present instance, I manufacture a plurality of 55 wheel blanks from a single sheet of metal with the spoke portions of the blanks so relatively positioned and formed as to interfit, and hence cut from the sheet substantially without wastage of material.

Having now stated the general method of 60 procedure, I will describe my invention in detail, reference being had to the accompanying drawings.

In the said drawings, 2 represents a rectangular sheet of metal of a thickness suitable 65 for the particular type of wheel being

manufactured. The character of the metal will be determined very largely by the service conditions to be imposed upon the wheel; that is to say, if the wheel is for use on a large, heavy vehicle or truck, the sheet 70 metal will be somewhat thicker than for wheels to be used on lighter passenger vehicles. The sheet metal, 2, is next stamped or sheared along the dotted lines 3-3 and 4-4, thus forming two blanks or members, 75 5 and 6, having respective spoke portions, 7 and 8. The part 6, as a matter of convenience, will be hereinafter referred to as the inner spoke portion, and the member 5 as the outer spoke portion. The members 5 80 and 6 are next shaped to cylindrical form as shown in Figs. 2 and 4, and preferably welded or otherwise joined respectively along the lines 9 and 10. Up to this stage of manufacture there need be no difference 85 between the members 5 and 6 and they could be used interchangeably for the manufacture of either the outer or inner spoke portion of the wheel. When the blank is to be used for the inner portion of the wheel, I prefer 90 next to shape the spoked end of the blank outwardly and at substantially right angles thereto, thus producing a flat, central, imperforate portion, 12, and a smaller 95 rectangularly disposed portion or flange as is shown in Figs. 2 and 3. I assemble the outer and inner spoke portions of the wheel centrally with and upon the wheel hub, 14, as shown in Fig. 6, and I so form the interior portion, 15, of the wheel hub that it 100 can be assembled upon either the front or rear axles of any standard or approved automobile axle. The hub, 14, is provided with the usual hub flange, 16; wherein I form a plurality of bolt holes, 17, for the 105 reception of bolts, 18 (see Fig. 6), which pass through the perforations, 19, in the inner spoke portion and thereby firmly secure same upon the flange.

As stated in the opening of the specification, it is an object of my invention to provide a true suspension-type wheel, and to this end it is necessary to tension the spokes. This I accomplish in a very simple manner. I first secure the end portions, 20, of the spokes in the wheel felly. This is done by moving the outer and inner body portions into the widely separated positions shown by means of dotted lines in Fig. 5. This permits placement of the spoke ends, 22, in the receiving slots, 22^a, of the felly, or other peripheral member. The outer and inner spoke portions are then moved to the positions shown by means of the full lines in Fig. 5. This forces the spoke-ends into 125 their slots and they are then secured in any suitable manner, a number of ways being described hereinafter. The full-line position, shown in Fig. 5, finds the outer and inner body members in closer relation than 130

they occupy in the final wheel. The ends of the spokes having been secured in the slots or holes of the felly portion, and the two body portions being then in the condition shown by full lines in Fig. 5, the hub is forcibly thrust into the hub-holes of the two body members. It will be noted that the hub is provided with a shoulder, 14'. This shoulder engages the inner edge of the outer body member, leaving the hub flange, 16, distant from the other member of the wheel body. Thereupon the bolts, 18, are put in place and the inner or back member of the body is forcibly drawn back 10 against the flange, 16, of the hub. Thus the central portions of the body members are separated at the hub and obviously this separation being resisted by the felly or peripheral member results in placing the 20 whole wheel under tension. Thus I produce a wheel of the true suspension type with all the advantages of that type, and without the disadvantages of so-called wire wheels. The outer spoke member of the 25 wheel body is formed in the same manner as the inner spoke portion, but inasmuch as it does not bolt against a flange, I simply curve the central portion, 22', thus producing a resilient hub center or circular elbow 30 between the spokes and the hub. The advantages of the resilient hub or spoke center are of primary importance.

I have not described the felly portion of the wheel in detail thus far for the reason 35 that this can be modified in many ways without departing from the invention, and I have illustrated a number of different modifications in the drawings which I shall describe in detail hereinafter. The felly 40 construction shown in Figs. 5 and 6 is of a type adapted to receive a demountable rim, the flange portions 24 and 25 being provided for that purpose.

In Figs. 7, 8 and 9 I have illustrated the 45 wheel with a demountable rim, 26, mounted thereon, in which is carried the usual pneumatic tire 27. The tire-containing demountable rim, 26, is of the straight side type, having integral side flanges, and is 50 secured demountably upon the wheel felly by means of a plurality of bolts, 28, upon which the wedge lugs, 29, are mounted, and which are forced into position between the flange, 24, of the wheel and the demountable rim, thus seating the demountable rim 55 firmly upon the back flange, 25, in a manner similar to that in which a demountable rim is to-day mounted upon a wooden wheel having a felly band formed with a similar 60 back flange. It will be understood that the wedge lug, 29, is forced into place by means of the nut, 30, operating upon the threaded end of the bolt, 28.

The wheel structure shown in Figs. 8 and 65 9 is practically the same as that shown

in Fig. 6 except as to a few details. In Fig. 8 a rear wheel construction is shown, a brake-drum, 35, being secured to the flange, 16, of the hub. In this instance, also, nipples, 36, are formed on the inner 70 spoke portion and enter openings provided therefor in the hub flange. These nipples form centering and alining means between the hub flange and the spoke portion and also serve as a clutch connection between 75 the parts to prevent relative rotation thereof. The same nipple construction is shown in Fig. 9; also a slightly modified connection between the spoke portions and the felly is also shown; that is to say, the end 80 portions, 37, are brought through slots formed in the side walls, 38, and 39, of the felly and there secured, instead of being entered through the cylindrical bottom portion of the felly. 85

In Fig. 10 I have shown my invention as embodied in a wheel in which the felly band, 40, is a simple band instead of a channel, being composed of a central, cylindrical portion, rear conical flange, 41, and 90 front, depending flange, 42. The spoke ends in this instance are secured in the felly band in the manner already described.

In Fig. 11 a modification is shown corresponding closely to that form shown in Fig. 10 except that the inner and outer spoke 95 portions do not cross, as in the wheels previously described.

Fig. 12 illustrates a structure of the type which I prefer to use when a more rigid 100 wheel is desired. In this instance I provide inner and outer spoke portions, 43 and 44, which are secured to the hub in the usual manner, but both of which in this instance are secured in the radial outer flange, 42, 105 of the wheel felly. Intermediate of these parts, I place another spoke portion, 45, which is secured to the hub preferably by a number of rivets, 46, and the spokes of which are substantially parallel to the 110 spokes of the outer portion, 44. The ends of the spokes, 47, are welded or fastened in holes in the peripheral band, at points closely adjacent the back flange thereof.

Those forms of my invention so far described are adapted to straight side tires, but it will be understood that my invention is not limited in any wise to the particular construction of the tire, and in Fig. 13 I have illustrated my wheel as embodied in, 115 or for, a clincher tire. In this instance no demountable rim is shown, the pneumatic tire being secured in the combined felly and tire receiving band or rim, 48.

Fig. 14 illustrates a modification of my 125 invention as embodied in a rear or driving wheel of another type. In this instance the hub, 50, is provided with an outer end flange, 51, and the inner portions, 52 and 53, of the spoke portions of the wheel, are 130

arranged between this flange, 51, and the wall, 54, of the brake-drum, 55. To hold the spoke portions in proper spaced relation I provide a spacing ring, 56, the various parts being rigidly secured together by means of a plurality of bolts, 57. In Fig. 15 I have illustrated a wheel construction particularly for use with heavy vehicles such as trucks. While this particular structure is a rear or driving wheel, it will be understood that the general features thereof may be embodied in the front or steering wheel. In this instance the hub, 60, is provided with a flange, 61, to the inner side of which is fastened a metallic disk member, 63. The outer edge of the metallic disk member, 63, is formed over a pair of annular bands, 65 and 66, the inner band, 66, constituting a felly and being suitably reinforced by ribs, 67, and the outer band, 65, being in the nature of a tire-carrying rim upon which a solid tire, 68, is mounted in this instance. As a support for the wheel in addition to the disk, 63, I provide a plurality of spoke portions or blanks, 69, 70 and 71. The innermost spoke blank, 69, is fastened to the hub flange by the bolts, 72, which serve also to bind the disk, 63, and the brake drum to the flange. The spoke blank portions, 70 and 71, in this instance are secured together adjacent the hub by means of bolts, 73, and the innermost end portions, 74 and 75, are shaped to rest upon the wheel hub in which position they are secured in any suitable manner. The outer or end portions of all spoke blanks are secured in the felly member, 66, in any suitable way, as for example, by entering them into slots formed for that purpose, and by welding them therein. A very rigid lateral structure is obtained by extending the spokes of the spoke member, 69, outwardly and the spokes of the spoke portion, 70, inwardly. In this instance the spokes extend beyond the center line. The structure described provides a light truck wheel, but which is amply strong to withstand service conditions and at the same time resilient enough greatly to aid in absorbing some of the road shocks and thus reduce the wear and tear upon the automobile parts.

In Fig. 16 I have illustrated still another type of truck wheel which is in effect a dual wheel supporting, however, a single tire band. In this instance I provide a hub, 80, of usual or desired construction, which contains the usual back flange, 81, to which the brake-drum, 82, is secured. The wheel shown is of the internal gear drive type having also secured to the hub flange the internal gear member, 83. The bolts, 84, serve not only to fasten the brake-drum and internal gear member to the hub flange, but also to secure the disk member, 85, which

has its inner portion, 86, in engagement with the body of the hub and its outer portion, 87, formed at substantially right angles to the plane of the wheel, and providing a seat for the rigid felly-band or member, 88. Upon the felly, 88, is mounted a solid tire, 89, by metallic engagement of its band, 90, with the felly-band, 88. In addition to the disk, 85, for supporting the felly band, or forming a connection between the hub and felly-band, I also employ spoke members, 91, 92, 93 and 94 which have the resilient spoke centers before described. The innermost member is secured to the hub-flange by means of the aforementioned bolts, 84. The outermost member, 94, is secured to the hub as by means of rivets, 96, and the intermediate spoke members, 92, and 93, are mutually connected by means of the short bolts, 97. The outermost portions of all spokes are secured in the felly-band, as indicated, and the spoke portions are tensioned in that same general way which has already been described; and especially by drawing the members, 92, 93, together as by means of the bolts shown; that is to say, by securing the spoke-ends in the felly with the spoke portions closer together than they occupy ultimately in the finished wheel and then moving the opposed centers of the body members away from each other and there securing them.

Fig. 17 illustrates, in detail, a so-called quick detachable tire-rim having a main or body portion, 100, and a detachable side flange, 101. The end portions of the spokes, 102 and 103, are in this instance inserted into openings or slots provided therefor in the band, 100, and then welded permanently to unite them with the band. In this manner they become an integral part of the band and their line of juncture is indicated only by means of dotted lines.

In Fig. 18 I have illustrated a demountable rim of the quick-detachable type composed of a main or body portion, 105, and a detachable side flange, 106. The demountable rim is seated upon the band, 107, of the wheel which is provided with the conical front and back flanges, 108 and 109, for co-action therewith. The demountable rim is thus held away from the band, 107, thus forming an annular space, 110. In this embodiment of my invention I may insert the spokes, 111, and 112, into slots provided in the band, 107, permitting the end portions, 113, and 114, to project into the annular space, 110. Incidentally the projecting ends, 111', of the spokes, 111, may serve as felly studs to assist in centering the demountable rim on the wheel. In this instance the spokes may be either welded or crimped in the holes of the member, 107, as about to be described.

In Figs. 19, 20, 21 and 22, I have illus-

trated means of fastening the spoke-ends in the peripheral band whatever its kind. Fig. 19 is a plan view of the wheel band, which is provided with spaced slots, 120 and 121, and in this instance the spoke ends are crimped, as shown at 122. When the ends are thus crimped in the slots, they are thereby firmly and rigidly locked to the peripheral band. Fig. 20 is a plan view of a wheel band illustrating the shape and positions of the spoke-end slots. Figs. 21 and 22 are detail views illustrating the manner of welding the spoke-ends in the wheel band. In Fig. 21 the first operation is shown where-
5 in the spoke-end projects into the slot, 125, in the band, 126, the extreme end portion, 127, extending above the band. In the welding and finishing operations (indicated as completed in Fig. 22) the ends are
10 made integral with the band, completely filling the slots; and the projecting portions, 127, are obliterated and made flush with the surface of the band. Thus the
15 spokes are integrally united with the peripheral metal band. In every such case
20 the tensioning of the wheel follows the operation of fastening the spokes in the peripheral band.

Fig. 23 is an enlarged detail illustrating
30 a wheel embodying my invention and including a demountable rim, the demountable rim and rim-supporting channel being of the construction shown in Figs. 8 and 9 bearing similar reference numerals. In this in-
35 stance, however, the spokes are secured in the felly-band or channel in a slightly different manner. The spoke-ends are inserted through slots in the felly and the extreme end portions, 140, are bent down against the
40 bottom of the channel, to which they may also be welded.

Fig. 24 is a cross-section illustrating a felly band or demountable rim-carrying seat of the general form shown in Figs. 10, 11 and
45 12. In this instance, however, the spoke end, 141, is welded in a slot provided in the front flange of the band and may even have an end portion, 142 (indicated by means of dotted lines), formed parallel with and se-
50 cured to the flange, in the same manner in which the end portions, 140, are united in the structure shown in Fig. 23.

In Fig. 25 I have illustrated (upon an enlarged scale) the union of the hub and body members of the form illustrated in Fig. 8, as the parts have already been described, and are indicated by the same reference marks.

From the foregoing description it is evi-
60 dent that my inventive idea may be embodied in structures of widely differing forms, many of which will immediately suggest themselves to one who is skilled in the art.

65 The advantages of my invention may be

summarized as follows:—The resilience of the wheel prevents too rigid resistance to lateral shocks and stresses. The wheel, weight for weight, is much stronger than the wheels in common use. Being in every
70 case practically, and in several cases actually, a single piece wheel, its parts cannot loosen or become squeaky, and it does not present joints which are subject to rust. Being a one-piece wheel it does not deteriorate by
75 usage in bad weather. Every part and surface is accessible and therefore the wheel is easy to surface finish and to clean. The wheel will give good service even when badly damaged by severe accident. Gen-
80 erally speaking the wheel has more elasticity combined with strength than either a wooden artillery wheel or a wire wheel. The wheel, weight for weight, is capable of carrying a heavier load than a wire wheel and a much
85 greater load in comparison with a wooden wheel of equal size and weight, and, as indicated, it is capable of maintaining greater side-wise stresses. The wheel is truly bal-
90 anced. It is substantially immune from dishing or crushing in either the hardest use or ordinary accidents. It is fully capable of withstanding the twists and tensions of severe strains in the transmission of power. As a necessary consequence of its
95 integrality all its parts are held in proper alinement. Vibrations are absorbed in the wheel to a great extent and not transmitted to the axles. The wheel obviously reduces the unsuspended load and transmits the load
100 stresses from the axle to the ground contact. If the wheel is fitted with a rubber tire its fatigue is less than any other kind of wheel. For the reasons given the wheel measurably increases the life of tires. By increasing
105 the hub length it is possible to insure all requisites of strength in wheels of large diameter and where the latter are used with pneumatic tires the tire life is of course in-
110 creased. The relatively flat surfaces and thick edges of the wheel permit it to be finished by any approved metal-finishing process and by the application of platings, paints and enamels of all kinds. Not the least of the advantages of my wheel is its
115 obvious beauty. A moment's consideration of the herein described process of manufac-
120 ture gives assurance that compared with other wheels for the same uses it is much less expensive to manufacture and to finish and the cost of its up-keep is practically *nil*.

Having thus described my invention, I claim as new and desire to secure by Letters Patent:—

1. The herein described metallic vehicle
125 wheel comprising a hub having a flange, an encircling, concentrically spaced wheel band, and outer and inner spoke blanks extending between and secured respectively to the hub and wheel band, the inner spoke blank being
130

secured to the hub flange in a plane substantially parallel to the vertical plane of the wheel, and the outer spoke blank being secured to the body of the hub.

- 5 2. The herein described metallic vehicle wheel comprising a hub having a flange, an encircling, concentrically spaced wheel band, and outer and inner spoke blanks extending between and secured respectively to the hub
- 10 10 and wheel band, the inner spoke blank being secured to the hub flange in a plane substantially parallel to the vertical plane of the wheel, and the outer spoke blank being secured to the body of the hub, said inner
- 15 15 spoke blank having its spoke portions extending angularly outward crossing the central vertical plane of the wheel, and the outer spoke blank having its spoke portions extending angularly inward crossing the
- 20 20 central vertical plane of the wheel.
- 25 3. The herein described metallic vehicle wheel comprising a hub having a flange, an encircling, concentrically spaced wheel band, and outer and inner spoke blanks extending between and secured respectively to the hub and wheel band, the inner spoke blank being secured to the hub flange in a plane substantially parallel to the vertical plane of the wheel, and the outer spoke blank being
- 30 30 secured to the body of the hub, said inner spoke blank having its spoke portions extending angularly outward crossing the central vertical plane of the wheel, and the outer spoke blank having its spoke portion
- 35 35 extending angularly inward crossing the central vertical plane of the wheel; and

said spokes being in tension between the hub and the wheel band.

4. The herein described sheet metal wheel that comprises a peripheral metal band, in combination with two sheet metal body members each composed of a center portion and a plurality of spokes integral therewith and radiating therefrom, said band containing as many spoke-end holes as there are 45 spokes in both members, the ends of said spokes being secured in respective holes, and means separating said members at the center and holding the wheel in tension.

5. The herein described sheet metal wheel 50 that comprises a peripheral metal band, in combination with two sheet metal body members each composed of a center portion and a plurality of spokes integral therewith and radiating therefrom, said band containing 55 spoke-end holes, the ends of said spokes being secured in said holes, and means separating said members at the center and thus holding the wheel in tension.

6. The herein described sheet metal wheel 60 that comprises a peripheral metal band, in combination with two sheet metal body members each composed of a center portion and a plurality of spokes integral therewith and radiating therefrom, said band containing as many spoke-end holes as there are 65 spokes in both members the ends of said spokes being welded in respective holes.

In testimony whereof I have hereunto set my hand this 7th day of May, 1918.

JOSEPH A. ANGLADA.
